UNITED STATES PATENT OFFICE.

LEVAN L. L. SWENSON, OF LONGMONT, COLORADO.

GOLD-SEPARATOR.

No. 917,906.

Specification of Letters Patent. Patented April 13, 1909.

Application filed June 15, 1908. Serial No. 438,567.

To all whom it may concern:

Be it known that I, LEVAN L. L. SWENSON, a citizen of the United States, residing at Longmont, in the county of Boulder and 5 State of Colorado, have invented new and useful Improvements in Gold-Separators, of which the following is a specification.

My invention pertains to means for separating gold from gold-bearing sand and other 10 substance; and it has for its object to provide a simple and inexpensive apparatus through the medium of which sand and the like may be efficiently robbed of the gold present therein, and this with but a minimum amount of attention on the part of the 15 attendant of the apparatus.

The invention will be fully understood from the following description and claim when the same are read in connection with 20 the drawings, accompanying and forming part of this specification, in which:

Figure 1 is a vertical section of the apparatus constituting the best practical embodiment of my invention known to me. Fig. 2 25 is a horizontal section taken in the plane indicated by the line 2—2 of Fig. 1, looking downward.

Similar letters designate corresponding parts in both views of the drawings, referring to which:

A is the receptacle of my novel apparatus which is preferably of globular form, and is provided at opposite points with projections 30 a, preferably trunnions, through the medium of which it is supported in a suitable frame A², and this in such manner that it may be oscillated, when deemed expedient, to increase the efficiency of the apparatus. On the bottom of the said receptacle A is arranged a fixed deflector b, and in the top of 40 the receptacle is formed an opening c surrounded by a horizontally disposed flange d.

C is an agent, preferably mercury or quicksilver, which is arranged in the receptacle A 45 to about the height illustrated, and has for its office to permit water, and sand or other gold-bearing substance to pass upwardly through it, and to take up gold and separate the same from the sand and water incidental 50 to such passage.

D is a flanged cover plate which is detachably secured, by bolts or otherwise, to the receptacle flange d, and is provided with a central opening e and with a plurality of 55 comparatively small openings f, grouped about the said central opening e. The open-

ing e is designed to receive and hold in an upright position a pipe E which extends down in the receptacle A to a point adjacent to the bottom thereof and is there provided with an annular cap F. This cap F is suitably secured on the lower end of the pipe E and is designed to surround and be separated by an intervening space from the before mentioned conical deflector b. Said cap 60 F is also designed to bear at its edge on the bottom of the receptacle A, and is provided with a plurality of apertures g for a purpose herein set forth. At a point above the receptacle A the pipe E is connected by a 70 coupling G with a pipe or other suitable conduit H, which latter is designed to lead from a source of water and gold-bearing sand supply.

In the practical use of my novel apparatus, 75 the water and gold-bearing sand pass downward through the pipe E and bring upward against the deflector b, after which the water and sand pass upward, as indicated by arrows, through the mercury or quicksilver C. 80 The gold commingled with the sand is, however, taken up by the said mercury or quicksilver, with the result that the water and sand alone pass out of the receptacle A through the openings f provided in the cover 85 plate D.

It will be readily understood from the foregoing that when the water and sand are turned outward and upward by the conical deflector b, the minute apertures g in the cap 90 F will distribute the water and sand throughout the mercury or quicksilver C, and in this way the thorough separation of the gold from the sand will be accelerated. The space in the receptacle A above the body of 95 mercury or quicksilver C is provided in order to enable said body to rise with the water and sand, and this latter also contributes to the efficiency of the apparatus in separating the gold from the sand.

When it is desired to discharge the commingled gold and mercury or quicksilver from the receptacle, the same may be readily accomplished by dumping the receptacle 100 after the pipe E is disconnected from the pipe H and the cover plate D is removed from the receptacle.

The apparatus herein illustrated and described constitutes the best practical embodiment of my invention of which I am 110 cognizant, but it is obvious that in the future practice of the invention such changes or

modifications may be made as fairly fall within the scope of my invention as defined in the claim appended.

It will be gathered from the foregoing that in practicing my invention the water and sand or other gold bearing substance pass down into the mercury or quicksilver and up through the same, and incidental to such passage the gold is taken in to the mercury.

Having described my invention, what I claim and desire to secure by Letters-Patent, is:

An apparatus for the purpose described, comprising suitable support, a receptacle of globular form having trunnions at opposite points journaled in the support and also having a conical deflector on its bottom and

an opening in its top, a cover plate detachably connected to the receptacle and having a plurality of small openings, a pipe extending down through said cover plate and having a cap at its lower end bearing on the bottom of the receptacle, around said deflector, and also having a plurality of small apertures in said cap, and a supply pipe detachably connected with the upper end of the first named pipe.

In testimony whereof I have hereunto set my hand in presence of two subscribing witnesses.

LEVAN L. L. SWENSON.
